CLAIM

The ornamental design for a “traffic alert device” as shown and described.

DESCRIPTION

FIG. 1 is a front view of a traffic alert device.

FIG. 2 is a rear view of the traffic alert device of FIG. 1.

FIG. 3 is a top view of the traffic alert device of FIG. 1.

FIG. 4 is a bottom view of the traffic alert device of FIG. 1.

FIG. 5 is a right side view of the traffic alert device of FIG. 1.

FIG. 6 is a left side view of the traffic alert device of FIG. 1.

FIG. 7 is a left, front perspective view of the traffic alert device of FIG. 1; and,

FIG. 8 is a left, rear perspective view of the traffic alert device of FIG. 1.

The lighter solid lines denote surfaces and contours of the traffic alert device that form no part of the claimed design. The broken lines in the drawings depict portions of the traffic alert device that form no part of the claimed design.

1 Claim, 8 Drawing Sheets
